US00D586803S

(12) **United States Design Patent**
Whitehorn et al.

(10) **Patent No.:** US D586,803 S
(45) **Date of Patent:** ** Feb. 17, 2009

(54) **WEDGE-SHAPED ELECTRONIC MEDIA READER**

KR 30-2004-0025424 7/2005

(75) Inventors: **Symon J. Whitehorn**, Sausalito, CA (US); **Gregg E. Zehr**, Los Gatos, CA (US)

(73) Assignee: **Amazon Technologies Inc.**, Seattle, WA (US)

(**) Term: **14 Years**

(21) Appl. No.: **29/246,295**

(22) Filed: **Mar. 29, 2006**

(51) **LOC (9) Cl. 14-02**

(52) **U.S. Cl. D14/346; D14/439**

(58) **Field of Classification Search D14/341, D14/342, 343, 344, 345, 346, 347, 420, 426, D14/427, 432, 439, 440, 441, 448, 496, 125, D14/137, 129, 130, 138, 250, 389, 147, 218, D14/247, 248, 156; D10/65, 104; D13/168; D18/6, 7; D21/329, 686; 455/90.3, 556.1, 455/556.2, 575.1, 575.3, 575.4; 379/433.01, 379/433.04, 433.06, 433.07; 361/814; 341/22; 345/169, 173**

(57) **CLAIM**

The ornamental design for a wedge-shaped electronic media reader, as shown and described.

DESCRIPTION

FIG. 1 is a perspective view of a wedge-shaped electronic media reader.

FIG. 2 is a front plan view of the wedge-shaped electronic media reader of FIG. 1;

FIG. 3 is a left side elevation view of the wedge-shaped electronic media reader of FIG. 1;

FIG. 4 is a bottom elevation view of the wedge-shaped electronic media reader of FIG. 1;

FIG. 5 is a back plan view of the wedge-shaped electronic media reader of FIG. 1;

FIG. 6 is a right side elevation view of the wedge-shaped electronic media reader of FIG. 1; and,

FIG. 7 is a top elevation view of the wedge-shaped electronic media reader of FIG. 1.

The broken lines are directed to environment and are for illustrative purposes only.

The broken lines form no part of the claimed design.
